(57) **CLAIM**

The ornamental design for a fish tape leader, as shown and described.

DESCRIPTION

FIG. 1 is a perspective view of the fish tape leader with a tape extending therefrom;

FIG. 2 is an exploded perspective view thereof;

FIG. 3 is a side view thereof;

FIG. 4 is a front view thereof; and,

FIG. 5 is a rear view thereof.

The broken lines shown represent unclaimed subject matter and form no part of the claimed design.
